UNITED STATES PATENT OFFICE.

ERNEST W. DUNBAR, OF HUDSON, AND HERMAN WESTLING, OF BOSTON, MASSACHUSETTS, ASSIGNORS TO CAMBRIDGE RUBBER COMPANY, OF CAMBRIDGE, MASSACHUSETTS, A CORPORATION OF MASSACHUSETTS.

PROCESS FOR MANUFACTURING RUBBER SHOES.

Application filed May 5, 1924. Serial No. 711,006.

This invention relates to rubber footwear and will be herein disclosed in connection with the manufacture of rubber overshoes of the heelless or foot-hold type, it being understood, however, that many of the features of the invention are equally applicable to other types of rubber shoes.

It is the general object of the invention to improve both the methods of making rubber footwear, and also the construction of such footwear, with a view to effecting economies in its manufacture. Stated more specifically, the invention aims to reduce the number of parts required in the manufacture of a rubber shoe, to reduce the number of dies required in cutting out such parts as are necessary, to reduce the waste material, and to simplify the manufacturing operations.

The nature of the invention will be readily understood from the following description when read in connection with the accompanying drawings, and the novel features will be particularly pointed out in the appended claims.

Referring now to the drawings,

Figure 1 is a plan view of the upper of a foot-hold embodying the present invention;

Fig. 2 is a perspective view showing certain of the initial steps in the manufacture of a rubber shoe according to this invention;

Fig. 3 is a plan view of the sole blank of a shoe;

Fig. 4 is a plan view of a binder strip which may be used in the bottom of a shoe, if desired;

Fig. 5 is a perspective view of a foot-hold which has just been lasted;

Fig. 6 is a view similar to Fig. 5 showing a lasted shoe after it has been trimmed;

Fig. 7 is a view similar to Fig. 6 showing the shoe after the sole has been affixed thereto;

Fig. 8 is a side elevation of a finished foot-hold;

Fig. 9 is a perspective view showing one step in the manufacture of a bathing shoe according to the present invention; and

Fig. 10 is a view of a tool which may conveniently be used in making the shoe.

In the manufacture of the foot-hold shown, two parts only are essential, namely, an upper and a sole, whereas at least five

parts have been considered necessary heretofore. Referring first to Fig. 1, 2 indicates a blank for the upper of the shoe, this upper including a vamp and a back strap. The upper is made abnormally wide; that is, it has abnormally wide margins projecting beyond the edge of that part of the blank which will form the vamp of the finished shoe. The back strap sections 3-3 project rearwardly from the vamp.

Preferably the blank 2 is cut out of unlined sheet rubber. If a beading or reinforcement is to be used at the upper edge of the vamp, or if the toe portion of the shoe upper is to be made heavy or reinforced, it is preferable to mold or "emboss" these reinforcements on the stock by means of a suitable die or roll, as will readily be understood by those skilled in this art. Fig. 1 shows such a reinforcement or beading embossed on the upper margin of the vamp. Preferably the edge of each back strap section is first folded over upon itself, as clearly shown in Fig. 2, the turned over portion increasing in width from the shank toward the rearward extremity, so as to provide ample strength in the strap at the back of the heel. The edges of the blank are next coated with cement or rendered tacky in any convenient manner, as indicated by the shaded portion 4, Fig. 2, and the blank is then folded longitudinally and the tacky margins pressed together. This folded upper is then drawn over the last and located properly thereon, substantially as shown in Fig. 5, the joined margins of the upper extending longitudinally of the last in the form of a fin or flange 7. The upper is next pulled snugly over the last by pinching together the surplus portions of the two margins, thus increasing the height of the fin 7, this operation being continued until the vamp is drawn smoothly over the upper shaping surfaces of the last. The upper is held in this position by the adhesion between the joined margins which constitute the fin 7.

The back strap sections 3-3 are next brought together around the back of the last 6 and joined, as shown in Fig. 5, any surplus stock first being cut off, the surfaces that are to be united being cemented or rendered tacky in order to produce a more perfect union. The surplus portion of the upper forming the pin 7 is next cut off, this

operation being conveniently performed with shears. When this operation has been completed the wings or extensions of the vamp which now lie upon the bottom of the last are united by a butt joint or seam that extends longitudinally of the last from the shank to the toe tip. In order to cause these two parts to adhere more firmly, the portions at each side of the seam may be wheeled, and for this purpose we prefer to use a novel tool which we have devised and which is shown in Fig. 10. This tool comprises two wheels 18 adapted to bear simultaneously on the stock at opposite sides of the seam 8, the wheels being so inclined that they will force the stock at opposite sides of the seam together as the tool is rolled over the bottom of the shoe. The indentations or marks left by this tool are indicated in Fig. 20 6 at 9.

If a separate beading strip is used in the place of the integral beading indicated at 5, it can be applied at this time, and if a separate tip reinforcement, as indicated at 10, is used, this should also be applied at this stage in the process. Neither of these features, however, is essential.

After the trimming operation has been completed a smooth surface is left for the 30 reception of the sole 12. This sole is simply pressed on to the bottom of the shoe, as shown in Fig. 7, any surplus stock in the shank is trimmed off, and the remaining operations may be performed in any suitable manner. Usually the shoe is next varnished and then vulcanized. The finished shoe is shown in Fig. 8.

As above stated, the shoe consists essentially of two pieces, namely, an upper and a 40 sole, and it is devoid of the usual fabric lining. Of course, other parts may be added to the upper, if desired, but they are not essential. It is sometimes preferable to make the sole of more than one piece, and it is a 45 very common practice to include a binder strip, such as that indicated at 14 in Fig. 4, in the bottom of the shoe, this binder consisting of rubberized fabric and being placed immediately under the sole 12, as indicated 50 at 14, Fig. 7. Various other modifications may be made without departing from the spirit or scope of the invention.

It will be observed that in the shoe shown 55 the extensions of the vamp which lie upon the bottom of the last form, in reality, the insole of the shoe, while the part 12 constitutes the outsole. In other words, in this particular shoe the insole and back strap are both integral with the vamp.

60 As above stated, the invention is applicable to other forms of rubber footwear, and such footwear may include a heel portion. For example, Fig. 9 shows a step in the manufacture of a bathing shoe in accordance 65 with this invention. In this case, also, the

upper and insole are integral and the lasting operation is performed substantially as above described, except that the fin 17 extends the entire length of the bottom and up the back of the last. After this lasting operation has been completed the fin 7 is trimmed off, a back stay usually is applied to cover up the seam between the abutting edges of the upper at the back of the last, the outsole is applied, and desired ornamental pieces are attached to the upper in the proper locations, and the shoe is then vulcanized.

An especially important advantage of this invention is that it eliminates the necessity for different sizes of upper dies, the same size of upper blank being used in making all sizes of shoes. Obviously there is more surplus stock to be trimmed off in making a small shoe than a large one, but this is immaterial since all this surplus stock is returned to the mixing mills for re-working. The advantage of the small number of parts required in the manufacture of this shoe will be obvious to those skilled in this art. The elimination of the fabric lining also is advantageous both because it avoids the expense of this material, and also because it saves waste. That is, if the flanges 7 and 17, Figs. 5 and 9, contained fabric, it would be impossible to re-work this stock and use it again in the manufacture of other shoes. The manufacturing operations are greatly simplified, and consequently the labor expense involved in the manufacture of the 90 shoe is materially reduced.

While, as above stated, it is preferable to eliminate the fabric lining, it is contemplated that such a lining may be desired under some circumstances, and many of the features of the present invention may be used to advantage in a shoe which includes such a lining. For example, a lining may be placed in the inside of the bottom of the shoe shown in Fig. 8 in order to conceal the 100 seam in the bottom of the shoe, or for any other reason. Other parts of the shoe also may be lined. Where the trade demands such a lining, therefore, it may be supplied.

Having thus described our invention, what 115 we desire to claim as new is:

1. That improvement in the process of manufacturing rubber shoes which consists in providing an upper of excessive width, placing the upper on a last, and adhesively 120 securing the marginal edges of said upper together centrally upon the bottom of the last to hold the upper in its lasted position, with said joined portions forming a fin extending longitudinally of the last bottom.

2. That improvement in the process of manufacturing rubber shoes which consists in cutting an upper of excessive width from unlined sheet rubber, placing the upper on a last, adhesively securing the marginal por-

tions of said upper together centrally upon the bottom of the last to hold the upper in its lasted position, with the joined margins of the upper forming a fin extending longitudinally of the last bottom, trimming off said fin to provide a substantially smooth surface, applying the shoe sole to said surface, and then completing the manufacture of the shoe in any convenient manner.

10 3. That improvement in the process of manufacturing heelless rubber shoes which consists in providing an upper of unlined sheet rubber, said upper including a vamp with back strap sections integral with said

15 vamp and with abnormally wide margins at the lower portion of said vamp, folding said

vamp longitudinally upon itself, adhesively joining the margins of said vamp together, placing said vamp on a last with said joined margins extending longitudinally along the 20 bottom of the last in the form of a fin, drawing said vamp smoothly over the last and holding it in said condition by pinching the surplus stock in said margins together and thereby increasing the height of said fin, removing said fin, joining the ends of the back strap sections, and securing a sole to said vamp.

In testimony whereof we have hereunto signed our names to this specification.

ERNEST W. DUNBAR.
HERMAN WESTLING.
